UNITED STATES PATENT OFFICE.

ARTHUR E. LEVENE, OF SEATTLE, WASHINGTON.

SAFETY RAZOR.

Application filed July 5, 1921. Serial No. 482,367.

To all whom it may concern:

Be it known that I, ARTHUR E. LEVENE, a citizen of the United States, residing in Seattle, in the county of King and State of Washington, have invented a certain new and useful Improvement in Safety Razors, of which the following is a specification.

This invention relates to improvements in safety razors and the object of this improvement is to provide a safety razor that will clamp the blade throughout its entire length and in close proximity to its cutting edge and that will hold the blade securely and firmly in a viselike grip in such a manner as to most effectively prevent bending action and vibration of the said cutting edge, thereby preserving the edge and making the blade cut smoothly.

Another object is to provide a safety razor having a guard member that follows instead of precedes the cutting edge, thereby permitting the cutting edge to come in contact with the hair in its naturally upstanding position and to cut such hair off squarely instead of cutting the hair on a bevel or splitting the hair as is ordinarily done where the hair is bent over by contact with a guard member before the blade encounters the hair.

Still further objects are to provide a safety razor having a guard member disposed between the blade and the surface that is being shaved and having a blade gripping element opposite said guard member that overhangs or projects forwardly a short distance farther than said guard member.

Still further objects are to provide a safety razor that is simple in construction; not expensive to manufacture; that will not clog when shaving; that is easy to clean; that will hold the blade in any position to which it is adjusted and that will hold blades of several different standard forms of construction.

With the above and other objects in view, the invention consists in the novel construction, adaptation and combination of parts as will be more clearly hereinafter described and claimed.

In the accompanying drawings Figure 1 is a view in side elevation of a razor constructed in accordance with this invention the blade being removed. Fig. 2 is a view in elevation of one side of the device, the handle being shown in cross section as on broken line 2, 2 of Fig. 1. Fig. 3 is a view

in elevation of the outer side of the blade clamping element as on broken line 3, 3 of Fig. 1. Fig. 4 is an enlarged view in cross section on broken line 4, 4 of Fig. 2 showing a blade clamped in operative position. Fig. 5 is an enlarged sectional view on broken line 5, 5 of Fig. 2 showing the blade clamping jaws in an open position. Fig. 6 is a plan view of the inside of blade clamping member as it may appear after it is stamped out and before it is doubled or bent together. Fig. 7 is a plan view showing the flat side of one of the blades and Fig. 8 is a fragmentary sectional view on a much enlarged scale showing the viselike manner in which the blade holding elements grasp and clamp a blade in close proximity to its cutting edge.

Like reference numerals designate like parts throughout the several views.

Referring to the drawings, the numeral 10 designates a knurled handle having a forward end of reduced size that is bent as at 11 to give the handle the most convenient inclination with respect to the head of the 80 razor and that is threaded as at 12 for the reception of a thumb nut 13.

The head or blade clamping portion of the razor is formed of an outer plate 14 and an inner plate 15 that are connected by a 85 resilient or spring like upper curved section 16 which may be formed by weakening the piece of metal from which the plates are made at this point so that all of the bending will occur in the weakened portion and the 90 plates 14 and 15 will not be sprung out of shape. The weakening of the curved portion 16 may be done by cutting away all of the metal from the central portion as at 17 and then cutting groove 18 from the ends of 95 the slot 17 outwardly to each side of the piece of metal.

The reduced end of the handle 10 passes freely through a perforation in the inner plate 15 and is riveted or otherwise rigidly 100 secured to the outer plate 14 as more clearly shown in Fig. 4.

The forward edge of the outer plate 14 is tapered or rounded as at 19 to form a guard that terminates in a sharp blade gripping 105 edge 20 and the corners of such forward edge project outwardly as at 21 to form corner guards.

The inner plate 15 is spaced from the outer plate 14 throughout the greater portion of its length and toward its forward edge is bent toward the outer plate to form

an inclined portion 22 that terminates in a straight, relatively thin blade clamping edge 23 that overlaps or projects outwardly a short distance further than the blade clamping edge 20 of the outer plate 14.

The plates 14 and 15 are adapted to have a blade 24 inserted therebetween and the plate 15 is preferably provided with rigid studs 25 that serve as stops for the blade 24 and that may project into recesses 26 in the outer plate 14 when the two plates are securely clamped on a blade.

The blade 24 may be provided with outwardly protruding portions 27 that may be grasped by the fingers when the blade is being inserted in or removed from or adjusted within the clamping plates 14 and 15.

The blade 24 is just wide enough so that when it is inserted between the clamping plates and allowed to rest on the stops 25 the cutting edge of such blade will project outwardly just far enough from the blade clamping edges 20 and 23 to afford the adjustment best suited to the ordinary beard.

If desired the rear edge of the blade may be moved outwardly away from the stops 25 to cause the cutting edge of such blade to project further from the blade clamping jaws 20 and 23, thereby giving any adjustment desired.

When the blade 24 is clamped within the holder as shown in Figs. 4 and 8 it will be rigidly and securely supported throughout its entire length by the blade gripping edges 20 and 23, the inner gripping edge 23 engaging the blade 24 very near to its cutting edge and the outer blade gripping edge 20 engaging such blade a short distance farther from the cutting edge than the gripping edge 23.

The corner guards 21 completely shield the sharp corners of the blade and serve as supports that prevent any outward curvature of the blade due to the overhanging position of the blade clamping edge 23 with respect to the blade clamping edge 20.

It has been found by experiment that the blade will cut better and will hold a cutting edge longer when the inner clamping edge 23 overhangs the outer clamping edge 20 than it will if the two edges are even or if the outer edge 20 overhangs the inner clamping edge 23.

The plates 14 and 15 are urged together with considerable force when the thumb nut 13 is tightened thus clamping the blade 24 firmly and in a vise like grip throughout its entire length and very near its cutting edge so that the blade will be free from bending action and free from vibration.

The blade is only gripped adjacent its cutting edge, the rear portions of the blade being unsupported and freely disposed between the plates 14 and 15.

From the foregoing description it will be

seen that there is no guard of any form except the corner guards 21 that precede the cutting edge of the blade so that the cutting edge of the blade is permitted to come in contact with the hair while such hair is in an upstanding position and will cut the hair off squarely without splitting the same or cutting it on a bevel as is done when the hair is bent over by a guard that precedes the blade.

The guard member of this razor is the rounded surface 19 that is disposed between the blade and the surface that is being shaved, that follows the cutting edge of the blade and that normally prevents such cutting edge from entering the skin. In the usual type of safety razor the guard member is outside of the blade and overhangs or precedes the cutting edge of such blade.

The thumb nut 13 is easy and convenient to operate and forms a simple means by which a powerful clamping pressure may be exerted on the plates 14 and 15 to grip the blade in a viselike grip.

If desired the plates 14 and 15 may be made from two separate pieces instead of from one piece as shown.

This razor will not clog when used on a long and heavy beard and its cutting action is substantially the same as that of an ordinary razor that has no guard.

This razor will hold a number of ordinary types of safety razor blades that are now on the market and are similar to the blade 24.

The foregoing description taken in connection with the accompanying drawings clearly discloses the principles of construction and method of operation of this safety razor, but, it will be understood that this disclosure is merely illustrative and that such changes in construction may be made as are within the scope and spirit of the invention as outlined by the following claims.

What I claim is:

1. A safety razor including two spaced apart plates having blade clamping edges arranged to engage with and firmly clamp a blade throughout its entire length and in close proximity to its cutting edge, both of said clamping edges terminating short of the cutting edge of the blade and the clamping edge of the outermost plate being beveled on the exterior to form a guard member that follows the cutting edge of the blade.

2. In a safety razor the combination with a blade, of two plates spaced apart for the reception therebetween of said blade and having clamping edges arranged to firmly clamp a blade throughout its entire length and in close proximity to its cutting edge only, the innermost clamping edge protruding slightly farther than the outermost clamping edge but terminating short of the cutting edge of the blade and the outermost

clamping edge being externally beveled to form a guard member that follows the cutting edge of the blade.

3. In a safety razor the combination with
5 a blade, of two plates spaced apart for the reception therebetween of said blade and having straight clamping edges arranged to firmly grasp a blade in close proximity to its cutting edge only, the innermost clamping
10 edge overhanging the outermost clamping edge but terminating short of the edge of the blade and the outermost clamping edge being beveled on the exterior to form a guard that follows the cutting edge of the
15 blade, a handle connected with said plates and means for forcing said plates together.

4. A safety razor comprising a head

formed of a single piece of metal bent double so that its two edges come substantially opposite each other to form blade clamping 20 jaws, the said metal being weakened by cutting away a portion of the same at the location of the bend and the inner portion of said head having an opening extending therethrough, a handle projecting through the opening in the inner portion of said head and rigidly secured to the outer portion of said head and means threaded on said handle and arranged to be screwed against the inner side of said head to force 25 the gripping edges of said head together.

In witness whereof, I hereunto subscribe my name this 20th day of June, A. D. 1921.

ARTHUR E. LEVENE.
